DESIGN FOR A WASHING MACHINE

Luke J. Strauss and Raymond E. Rousseau,
Buffalo, N. Y.

Application December 13, 1938, Serial No. 81,764

Term of patent 14 years

To all whom it may concern:

Be it known that we, Luke J. Strauss and Raymond E. Rousseau, citizens of the United States, residing at Buffalo, in the county of Erie and State of New York, have invented a new, original, and ornamental Design for a Washing Machine, of which the following is a specification, reference being had to the accompanying drawing, forming part thereof. This application is a continuation-in-part of our pending application Serial No. D-71,217, filed August 20, 1937.

Fig. 1 is a perspective view of a washing ma-

chine showing our design. The other side of the machine is like the side shown.

Fig. 2 is a fragmentary vertical sectional view on a larger scale and taken on line 2—2 of Fig. 1.

The essential features of the design reside in the lower portions as indicated by heavy black lines.

We claim:

The ornamental design for a washing machine, substantially as shown and described.

LUKE J. STRAUSS.

RAYMOND E. ROUSSEAU.
